CLAIM

The ornamental design for a telephone handset and stand, as shown and described.

DESCRIPTION

FIGS. 1 and 2 are respectively front and rear elevational views of a telephone handset and stand showing my new design in cradled relationship;

FIGS. 3 and 4 are respectively left and right side elevational views thereof;

FIGS. 5 and 6 are respectively top and bottom plan views thereof;

FIG. 7 is a front, top and right side perspective view thereof; and

FIG. 8 is a perspective view similar to FIG. 7, with the handset inverted and spaced apart from the stand for additional disclosure of surface appearance.

FIG. 1

FIG. 2

FIG. 3

FIG. 4

FIG. 5

FIG. 6

FIG. 7

FIG. 8
